UNITED STATES PATENT OFFICE

JOSEPH H. PRICE, OF CAPE GIRARDEAU, MISSOURI.

SPARK AND THROTTLE LEVER LOCK.

1,331,873.

Specification of Letters Patent. Patented Feb. 24, 1920.

Application filed September 25, 1919. Serial No. 326,168.

To all whom it may concern:

Be it known that I, JOSEPH H. PRICE, a citizen of the United States, and a resident of Cape Girardeau, in the county of Cape Girardeau and State of Missouri, have invented certain new and useful Improvements in Spark and Throttle Lever Locks, of which the following is a specification.

My present invention relates generally to locks and more particularly to an ignition and throttle lock for Ford machines, my object being the provision of a simple inexpensive device which may be readily applied and removed and which will in its operative position effectively prevent manipulation of either the throttle lever or the spark lever from the fully closed and retarded positions respectively.

A further object is the provision of a simple inexpensive device of this nature, which will permit of the use of a pad lock, allowing the user the free choice as between key and keyless or combination locks.

A still further object is the provision of a simple inexpensive device, in which the active locking elements will, in the effective position, be fully protected beneath the gear casing adjacent the upper end of the steering post and around the steering post itself.

With the above general objects, the further and more specific objects of my invention, as well as the resulting advantages, will be more plainly understood from the following description, reference being had to the accompanying drawing, which forms a part of this specification, and in which,

Figure 1 is a top plan view showing the practical application of my invention, in locked position,

Fig. 2 is a vertical sectional view taken substantially on line 2—2 of Fig. 1,

Fig. 3 is a top plan view of the securing means provided by my invention in unlocked position, and

Fig. 4 is a cross section showing a slightly different form.

Referring now to these figures, and particularly to Figs. 1 and 2, have shown the steering post at 10, of a Ford machine, adjacent to the upper end of which is an enlarged annular gear casing 11, this gear casing being spaced above the quadrant 12, over which the spark lever 13 and throttle lever 14 operate.

As illustrated and as well known, the quadrant projects laterally from the steer-

ing post around the forward portion thereof and has at its two rear ends upright lugs 15 against which the spark lever and throttle lever abut in the fully retarded and closed 60 positions respectively, which may, for the present purposes at least, be termed their inactive positions.

My invention aims to secure the levers 13 and 14 in their inactive positions by means 65 of a securing member consisting of a semi-circular block or body portion 16 arranged to seat on the quadrant 12 to whose shape it conforms, and provided with a semi-circular recess intermediate its straight side, as indicated at 17, which partially embraces the steering post immediately beneath the gear casing 11, the outer portions of its straight side engaging the spark and throttle levers to hold the latter immovable against the 75 lugs 15.

The upper surface of the body of block 16 of the securing member has recesses 18 in spaced relation extending from its straight edge and is provided with vertical openings 80 located adjacent to the inner ends of these recesses through which the inner annular extensions 19 of a pair of locking arms 20 depend.

The lower ends of the depending annular 85 portions 19 of locking arms 20 are fastened in any suitable manner, as by means of riveting, so as to hold these annular portions rotatable in the vertical openings of the block 16 and permit locking arms 20 to 90 swing in the recesses 18 and thus approximately flush with the upper surface of the block 16.

The locking arms 20 are curved as shown and provided with enlarged eyes 21 at their 95 free ends, their curvature being such as to adapt them to be shifted snugly around the steering post 10 to bring their eyes 21 closely adjacent to and in registry with one another for the reception of the shackle of a 100 lock generally indicated at 22 and which may, it is obvious, be of either a key controlled or keyless nature, leaving the user unlimited choice as to types and makes.

It will thus be noted that in the effected 105 position of the key, the two locking arms 20 snugly embracing that portion of the steering post opposite to the intermediate recess 17 of the block and are thus locked immediately below and in rigid relation beneath the casing 11, so that when locked, neither the outer or inner ends of the lock-

ing arms may be forced upwardly in an attempt to defeat the purposes of a lock on account of the gear casing 11.

It is further obvious that on account of the firm seat of the block or body of securing member upon the quadrant 12 it has a firm support and purchase which effectively coöperate with the remaining features and their relative location in promoting effectiveness of the lock as a whole and defeating attempts at unwarranted manipulation of the spark and throttle levers.

It will thus be seen that my invention proposes a construction and arrangement which will carry out the objects first above stated, and which will be simple and inexpensive, as well as durable and effective.

I claim:

1. The combination with a steering post having an enlarged annular gear casing, spark and throttle levers, a quadrant from which the said levers work, located in spaced relation below the gear casing, and having upright portions against which the levers are shiftable when inactive, of a securing means including a block arranged to be seated on the quadrant and partly embracing the steering post between the quadrant and the gear casing, said block having portions engageable with the spark and throttle levers to hold the latter immovable against the upright portions of the quadrant, a pair of curved locking arms pivotally connected at one end to the block in spaced relation and movable to embrace the remaining portion of the steering post beneath the gear casing, and a lock engageable with the free ends of said locking arms to hold the same immovable in inactive position.
2. The combination with a steering post having an enlarged annular gear casing, spark and throttle levers, a quadrant from which the said levers work, located in spaced relation below the gear casing, and having upright portions against which the levers are shiftable when inactive, of a securing means including a block arranged to be seated on the quadrant and partly embracing the steering post between the quadrant and the gear casing, said block having portions engageable with the spark and throttle levers to hold the latter immovable against the upright portions of the quadrant, a pair of curved locking arms pivotally connected at one end to the block in spaced relation and movable to embrace the remaining portion of the steering post beneath the gear casing, said locking arms having enlarged eyes at their free ends disposed adjacent to

one another, when the arms are in active position, and a lock having a shackle engageable through the eyes of the two locking arms, as and for the purpose described.

3. The combination with a steering post, its gear casing, the control levers and quadrant on which the control levers work located below the gear casing, a securing member including a body portion seatable on the quadrant and engageable with the control levers, and movable arms carried by the said body portion, and shiftable into embracing relation around the steering post beneath the said gear casing, said arms being provided with lock receiving means at their free ends, as and for the purpose described.

4. A securing device of the character described, including a body portion, having a recess intermediate the ends of one face and provided with lateral projecting and engaging surfaces at the opposite sides of said recess and curved locking arms pivotally connected to the body portion at opposite sides of its said recess, said locking arms being shifted toward and away from one another and having lock receiving means at their free ends, as described.

5. A spark and throttle lever securing device, for automobile control, having a steering post adjacent to said levers, and a stationary quadrant against portions of which the said levers abut in their inactive positions, consisting of a block or body portion seatable on the quadrant, and having portions engageable with the levers to hold the latter immovable in abutting relation with the quadrant, steering post embracing arms pivoted at one end to the said body to embrace the steering post and hold the body stationarily upon the quadrant provided with lock receiving means at their free ends, as described.

6. A securing device of the character described, consisting of a body or block having a vertical recess at one side and lateral engaging surfaces upon opposite sides of said recess, said body being provided with recesses in its upper face in spaced apart relation, and with vertical openings adjacent to the inner portions of said last mentioned recesses and curved lock arms, the inner portions of which are shifted in the last mentioned recesses of the block and provided with annular extensions rotatably mounted through the said openings of the block, the outer free ends of said arms being provided with lock receiving eyes, as described.

JOSEPH H. PRICE.
